CHARLES E. DATH, OF CHICAGO, ILLINOIS, ASSIGNOR TO WILLIAM H. MINER, OF CHICAGO, ILLINOIS.

RAILWAY DRAFT-SILLS.

1,126,718.

Specification of Letters Patent.

Patented Feb. 2, 1915.

Application filed February 5, 1914. Serial No. 316,712.

To all whom it may concern:

Be it known that I, CHARLES E. DATH, a citizen of the United States, residing at Chicago, in the county of Cook and State 5 of Illinois, have invented a certain new and useful Improvement in Railway Draft-Sills, of which the following is a full, clear, concise, and exact description, reference being had to the accompanying drawings, forming 10 a part of this specification.

My invention relates to an improvement in draft-sills for railway cars.

One object of my invention is to provide draft-sills of simple, efficient and strong 15 construction; and a further object is to provide draft-sills that may be readily applied to railway cars having wooden underframes.

My invention is fully described in the 20 specification, and shown in the accompanying drawings, in which—

Figure 1 is a top plan view of draft-sills secured to center-sills and embodying my invention; Fig. 2 is a vertical longitudinal 25 section on line 2—2 of Fig. 1; Fig. 3 is a cross-section on line 3—3 of Fig. 2; Fig. 4 is a cross-section on line 4—4 of Fig. 2; and Fig. 5 is a cross-section on line 5—5 of Fig. 2.

Referring to the drawings, the numerals 30 6—6 represent center-sills of an ordinary car frame; 7 the floor of the car; 8 the end sill; 9 the buffer block; 10 the body bolster provided with the upper flange 11; 12 the 35 lower flange, and having on its lower face the recess 13 to receive the boss of the truck center plate, the said bolster being also provided with the vertical opening 14 to receive a king pin. The foregoing parts are 40 of well known construction. In the form of bolster shown in the drawings, the body-bolster center plate 15 is made integral with the bolster. The draft-arms 16 are two in number for each end of the car, each being 45 adapted for attachment to a center-sill. As the draft-arms at either end of the car are counterparts of each other, we will describe one of said arms. In preferable construction, each of said arms consists of a forward 50 portion 17, and a rearward portion 18. The forward portion 17 is provided with the stop-shoulders 19, 20 and 21, which are preferably integral with the member 17, and serve their usual function in the draft 55 rigging for the car. The member 17 is provided with a preferably integral horn 22, 60 adapted to engage against the end-sill 8, as indicated at the numeral 23 in Fig. 2 of the drawings. The said member 17 is forwardly extended to the forward face 24 of 65 the buffer block 9, and at its rearward end abuts against the front face 25 of the body-bolster 10. In preferable construction a bolt 26 is passed through the buffer block 9 and the member 17 of the draft-arm and 70 the draw-bar carry iron 27. A bolt 28 secures the member 17 to the end-sill 8, and suitable bolts 29—29 secure the member 17 to the car center-sill 6. Each member 17 is provided with an upper flange 30, adapted 75 to engage the under face 31 of a center-sill 6, and with a lower flange 32 and intermediate such flanges with a longitudinal strengthening web 33. Each member 18 is in preferable construction I-shaped in cross- 80 section, the lower flange 34 converging upwardly and rearwardly toward the upper flange 35. The forward edge 36 of the member 18 engages against the rear face of the body-bolster, as indicated at the numeral 37 in Fig. 2 of the drawings. The member 18 is suitably secured to the adjacent center-sill 6 preferably by bolts 38—38 85 passing through the center-sill and through ways 39—39 vertically provided in the member 18. The member 18 is connected to the member 17 on each draft-sill by means passing both above and below the body-bolster. The means passing above the body-bolster preferably consists of a channel bar 40, 90 preferably integral with the member 18 and secured to the upper flange 30 of the member 17 by suitable means, preferably the rivets 41—41. The means connecting the member 18 to the member 17 passing underneath the body-bolster consists preferably of a bar 42 formed integrally with the member 18, suitably secured to the lower flange 32 of the member 17, preferably by the rivets 43—43, the said bar being of suitable conformation to pass around the body-bolster center plate 15. Bolts 44—44 may be employed to pass through the arm 40 and engage the bolster at one end and the adjacent center-sill at the other. 95 100 105

It will be observed that in the construction described pulling and buffing stresses are transmitted directly in a horizontal line

through the bolster, and that an unusually strong union of bolster and draft-arms is secured.

As clearly shown in Fig. 1 of the drawing, 5 the member 17 is located mostly on the inner side of the wooden center sills and the portion 18 is off-set outwardly as it passes the bolster in order to provide sufficient clearance for the portion of the bolster 10 forming the socket for the king pin. It will also be observed that the portions 40 and 42 of the member 18, being formed integrally with the latter, constitute a fork which straddles the bolster and the ends of the 15 portions forming the fork are secured to the member 17, thus forming an unusually rigid and substantial construction.

I claim:

1. In a car underframing, the combination with wooden center sills and body bolster, of a draft arm secured to the wooden sills, said draft arm comprising a forward member serving as a stop of a draft rigging and a rearward member connected to the 25 forward member, the rearward member having integral fork arms between which the body bolster is arranged.

2. In underframing for railway cars, the combination with wooden sills and a body bolster, of a draft arm comprising a front 30 and a rear member, the front member being located mostly to the inner side of the center sill and the rear member being off-set outwardly from the front member where it passes the bolster, the bolster passing 35 through said draft arm.

3. In underframing for railway cars, the combination with center sills and body bolster, of a draft arm secured to each sill, 40 each draft arm comprising a front member the rear of which abuts the body bolster and a rear member having integral extensions passing above and below the body bolster and forming a fork between which the bolster is mounted, the ends of said extensions 45 being secured to the front member of the draft arm, the lower member of said fork being outwardly off-set where it passes the body bolster.

CHARLES E. DATH.
